UNITED STATES PATENT OFFICE

PAUL REHLÄNDER, OF BERLIN-CHARLOTTENBURG, GERMANY

METHOD OF MAKING A PHOTOGRAPHIC ELEMENT FOR COLOR PHOTOGRAPHY

Application filed April 2, 1932, Serial No. 602,772, and in Germany April 7, 1931.

This invention relates to color photography, more especially to taking, printing and reproducing photographs in natural colors. The object of my invention is to improve the method described in my copending application Ser. No. 496,803 filed November 19, 1930, and my patent specification No. 1,872,501.

In my former applications I have described a material for taking the photographs which 10 is provided with a screen of transparent and opaque squares or lines alternating regularly and lying in the same plain which screen is covered with a layer thinner than 0.1 m.m.

Now I have found that the production of 15 such material may be facilitated by applying a fine-grained photographic emulsion to the transparent support, preferably thinner than 0.1 m.m. and colored with a strong yellow dye-stuff which afterwards can easily be washed 20 out. Then an image of a black-and-white screen is projected through the transparent support upon that surface of the said photographic emulsion which is in contact with the rear side of the said transparent support. By 25 developing this light-impression, fixing, washing and drying I obtain a black-and-white screen covered by the base of the photographic emulsion used. Finally a panchromatic photographic emulsion is applied to the 30 free surface of the said base.

To obtain images showing natural colors a lens such as described in my copending application Ser. No. 496,804 may be inserted between the taking lens and the light-sensitized 35 material close to the latter.

The screen may consist of alternating dark and transparent lines or figures.

The invention is illustrated in the annexed drawing of which Fig. 1 shows a perpendicular cross-section through a photographic material composed according to the present invention. Figs. 2 and 3 illustrate two modifications of the screen.

Referring first to Fig. 1, *a* is the transparent support consisting of celluloid or glass, for instance. *b* indicates the screen produced in the surface of the fine-grained emulsion *c*, 60 contacting the layer *a*. *d* is the panchromatic emulsion. *e* represents a lens as described in my application Ser. No. 496,804.

In Fig. 2 the screen is formed by alternating dark and transparent lines or bands *f*, *f'* 65 respectively, whereas in Fig. 3 the screen has the configuration of a chess-board.

When employing this material for color photography, the view is taken by means of a suitable two- or three-colored diaphragm 70 thru the transparent support and the white-and-black screen upon the panchromatic emulsion.

I claim:—

The method of producing a light-sensitized 75 material for taking, copying and reproducing photographs in natural colors, which comprises coating a transparent support with a fine-grained emulsion containing a light-absorbing dye-stuff soluble in water, photographically copying a screen on that surface of the emulsion which contacts the said support, developing, fixing and washing, and then coating the other surface of the previous fine-grained emulsion employed with a 80 panchromatic emulsion. 85

PAUL REHLÄNDER.
